NONREFILLABLE ATTACHMENT

Jacob W. Schieber, Scranton, Pa.

Application October 29, 1936, Serial No. 108,286

3 Claims. (Cl. 215—22)

This invention relates to a non-refillable attachment for bottles, jugs and containers, and is designed primarily for use in connection with bottles containing high grade liquors, wines, perfumes, etc., but it is to be understood that the attachment, in accordance with this invention, may be employed in connection with any type of container, holding powder or pellets, for which it is found applicable.

10 The object of the invention is to provide, in a manner as hereinafter set forth, an attachment of the class referred to which, when in anchored position with respect to a bottle, will prevent the surreptitious refilling of the bottle after the 15 original contents of the latter have been discharged.

A further object of the invention is to provide, in a manner as hereinafter set forth, an attachment, for the purpose referred to, which 20 will permit a steady discharge, with no surging action, of the contents of a bottle when the latter is tilted from the vertical to beyond the horizontal, and further will prevent discharge from the bottle when the latter is disposed in a vertical 25 inverted position.

Further objects of the invention are to provide, in a manner as hereinafter set forth, a non-refillable attachment for bottles, jugs and containers, which is simple in its construction and 30 arrangement, readily installed with respect to the neck of a bottle, jug or container, strong, durable, compact, thoroughly efficient in the use intended thereby, and comparatively inexpensive to manufacture.

35 With the foregoing and other objects in view, the invention consists of the novel construction, combination and arrangement of parts as will be hereinafter more specifically described and as are illustrated in the accompanying drawing 40 wherein is shown an embodiment of the invention, but it is to be understood that changes, variations and modifications may be resorted to which fall within the scope of the invention as claimed.

45 In the drawing:—

Figure 1 is an elevation looking towards one side of the attachment.

50 Figure 2 is an elevation looking towards the inner face of one of the sections of the body part of the attachment disposed with respect to the neck of a bottle.

Figure 3 is a top plan view of the attachment.

55 Figure 4 is a sectional plan of the attachment when taken on line A—A Figure 2.

Figure 5 is a sectional plan of the attachment when taken on line B—B Figure 2.

Figure 6 is an elevation looking towards the inner face of the other section of the body part of the attachment with such section tilted for discharge of the contents of the bottle, 5

Figure 7 is a perspective view of the cage for the lower valve of the attachment, and

Figure 8 is a top plan view of a sealing annulus forming an element of the attachment. 10

Referring to the drawing, 1, 2, 3, 4 and 5 indicate respectively the body, breast, neck and mouth edge of a bottle and attaching lugs on the outer periphery of the neck. The lugs 5 are of the wedging type and coact with lugs 6 on the inner face of the attachment 7 for clamping the latter to the neck 3 and against the edge 4. When the attachment is connected to the bottle by the coacting lugs, it is furthermore secured to neck 3 by a body of cementitious material 8 15 interposed between the neck 3 and inner portion of attachment 7. 20

The attachment includes body part 9 formed of a pair of oppositely disposed inner facewise anchored together sections 10, 11 of like form 25 with this exception that the section 10 has lengthwise of its inner face a pair of spaced oppositely disposed grooves 12, 13 of like form and that in lieu of providing the inner face of section 11 with grooves 12, 13 it is formed lengthwise with 30 a pair of spaced oppositely disposed elongated ribs 14, 15 of like form which seat in the grooves 12, 13 respectively when the sections are anchored together. The grooves and the ribs are of less length than that of the sections and extend from the outer end to a point removed from the inner end of the sections. These latter are formed of any suitable material capable of being brazed, welded or cemented together. 35

The section 10, as well as the section 11 is 40 formed from one piece of material and it includes a semi-annular inner portion or part 16 formed with an inturned semi-circular rear flange 17 throughout its outer end, a semi-circular forward flange part 18 merging into the top of and extending inwardly from and overhanging flange 17, a semi-annular frustoconoidal part 19, integral at its inner end with the upper face of part 17 and a flat substantially rectangular outer part 20 which is of greater 50 length than the portion 16, flange 17, part 18 and part 19. The part 20 merges at its inner end into the upper face of flange 17 at the sides thereof. The part 20 in proximity to its inner end and adjacent its edges merges into the outer 55

face of part 18 at the sides of such outer face. The part 20 adjacent its sides merges into the sides of part 19 and inwardly adjacent its outer end merges into the outer end of part 19. The 5 inner end of the side edges of part 20 are flush with the outer face of part 16. The latter, flange 17, part 18 and part 19 are outset with respect to the outer face of part 20. The flange 17 is outset with respect to flange 18 and the latter is 10 outset with respect to the major portion of part 19. The part 19 extends at an inward inclination from its inner to its outer end with respect to part 18. The part 20 at its outer end edge is formed centrally thereof with a semi-annular 15 extension 21 which has its inner face register with the wall of a groove 22 formed in the inner face of the part 20 at the outer end of the latter.

The end edges of the part 18 have sockets 23. The inner face of part 20 has a socket 24. When 20 the sections 10 and 11 are secured together the sockets 23, 24 of section 10 register with the sockets 23, 24 of section 10 and the registering sockets are to receive coupling members which 25 engage in the sections and connect the sections together in addition to brazing, welding and cementing the sections together. The manner of connecting the sections together by coupling members is shown with respect to the registering sockets 23 (Figure 4). The coupling members 30 shown are indicated at 25.

The inner side edges 8 of the part 19 are provided in spaced relation to the ends thereof with oppositely extending upwardly outwardly inclined grooves 27, 28. The inner face of part 20 35 is formed with a pair of spaced oppositely disposed upwardly extending grooves 29, 30 inclining inwardly from their rear to their outer ends and are disposed lengthwise of part 20. The 40 grooves 29, 30 are closed at their inner ends and open at their outer ends. The grooves 21, 28 open into the grooves 29, 30 through the inner sides of and intermediate the ends of said grooves 29, 30. The inner face of part 20 forwardly of grooves 29, 30 is formed with a pair of horizontal disposed endwise spaced grooves 31, 32. The 45 outer ends of the grooves 29, 30 open into the grooves 31, 32 from the lower sides and intermediate the ends of such sides. The inner end of the grooves 31, 32 are closed and the outer ends 50 are open. The inner face of part 20 is formed lengthwise thereof with a pair of spaced parallel grooves 33, 34 which are closed at their inner ends and open at their outer ends. The grooves 31, 32 open into the grooves 33, 34 through the 55 inner sides of and outwardly adjacent to the inner ends of the grooves 33, 34. The inner face of part 20 outwardly adjacent the grooves 31, 32 is formed with a pair of oppositely extending horizontally disposed inclined grooves 35, 36 60 which at one end open into the outer ends of the grooves 33, 34 and have other ends merge into each other and open into the inner end of groove 22.

The portion 16 and flange 17 coact to provide 65 a semi-annular shoulder 37. The flange 17 and part 18 coact to form a semi-annular shoulder 38. When the sections 10, 11 are anchored together in inner facewise relation, the parts 16 of said sections coact to provide the body part with an 70 inner annular portion 38a having its inner face provided with the lugs 6; the parts 16 and flanges 17 coact to form an internal rear annular flange; the flanges 17 and parts 18 coact to provide an internal rear annular flange overhanging the 75 rear flange; the parts 18 and 19 coact to provide

a valve chamber 39 closed at its outer end, open at its inner end, having its inner portion of uniform diameter, its outer portion frusto-tapered in contour and with the outer portion of greater length than its inner portion; the grooves 21, 28 of the parts 19 register to provide outlets for the valve chamber 39; the extensions 21 and grooves 22 of the parts 20 coact to provide an opening for the reception of a cork 40 for closing the attachment, as well as an outlet for the contents of the bottle and an air intake for the attachment; and the grooves 21, 28, 29, 30, 31, 32, 33, 34, 35, 36 of one part 20 register respectively with the grooves 27, 28, 29, 30, 31, 32, 33, 34, 35 and 36 of the other part 19 to provide the attachment with a pair of spaced oppositely disposed tortuous tubular conducting passages 41, 42 having their inner ends closed and their outer ends opening into the outlet provided by the registering extensions 21 and grooves 22. The intake for the passages 41, 42 are provided by the outlets for the valve chamber 39. The closed inner ends of the passages 41, 42 are arranged in proximity to, but outwardly of the inner portion of uniform diameter of the valve chamber. The passages 41, 42 are for selectively conducting off the contents of the bottle and for the admission of air to the valve chamber and bottle.

The attachment includes a pair of superposed valves 43, 44. The valve 43 is of globular form. The valve 44 is in the form of a disc of resilient material having a recess 45 in its upper face in which valve 43 seats when the bottle is upright. The valve 43 is of much greater weight than valve 44. The valves are formed from any suitable material.

Arranged within the body part 9 is a combined valve cage with guide element 46 consisting of an annulus 47 formed on its upper face with a circular row of spaced vertically disposed guide arms 48 of less length than the height of part 18 of a section. The arms 48 are arranged inwardly adjacent the edge 49 of the annulus. The arms 48 are of greater height than that of the valve 44. The latter when the attachment is in an upright 45 position seats on annulus 47 and is surrounded by the arms 48. The annulus 47 provides an intake for valve chamber 39. When the element 46 is arranged in body part 9, the upper face of annulus 47 bears against the lower faces of the parts 18 50 of sections 10, 11; the outer edge of the annulus bears against the inner edges of the flanges 17 of sections 10, 11; and the arms 48 bear against the inner side faces of the parts 18 of sections 10, 11.

The attachment includes a sealing element 49 which also constitutes a retainer for the element 46. The element 49 is in the form of a resilient gasket 50 for interposing between the inner face of the flanges 17 of sections 10, 11 and the mouth edge 4 of the bottle, and it is clamped in position and compressed when the attachment is secured to the bottle neck. The element 49 is of greater inner and outer diameter than that of annulus 47.

The valve 43 tends to maintain the valve 44 on its seat provided by that portion of the upper face of the annulus 47 which is surrounded by the arms 48.

If the bottle is tilted with respect to the horizontal to the right, the passage 41 constitutes a 70 fluid discharge passage and the passage 42 provides a combined fluid discharge and air intake passage. If the attachment is tilted with respect to the horizontal to the left, then the passage 42 forms a fluid discharge passage and the 75

passage 41 provides a combined fluid discharge and air intake passage. The parts of the attachment are so arranged to provide for discharge of the contents of the bottle after the attachment is disposed at an angle with respect to the horizontal and as the attachment, when extending downwardly, is moved towards the vertical, the flow decreases and completely stops when the attachment assumes an inverted vertical position. It is thought that the preventing of discharge from the bottle, when the attachment is in an inverted position and vertically disposed, is due to an air-trap effect within the attachment. The tubular or tortuous passages are of like form, oppositely disposed, having offset closed branches and so formed as to prevent the passage of a wire or other implement to hold valve 43 off of its seat to surreptitiously refill the bottle.

20 The attachment is for employment in connection with any form of container having a neck or an annular extended intake or filling member. The term container is also meant to imply a bottle or a jug. The term neck is also meant to imply an annular extended intake or filling member.

What I claim is:—

1. In a non-refillable attachment for containers of the neck type, a structure having respectively an annular inner portion for connection to the container neck, an inwardly extending inner flange forming means at the outer end of said inner portion, an inwardly extending outer flange forming means overhanging said inner flange forming means and means coacting with said outer flange forming means to provide a valve chamber for the reception of a pair of superposed valves, said chamber having an inner portion of uniform diameter and an outer portion of frusto-conoidal contour, said structure being formed respectively with means to constitute a closable fluid discharge outlet and air intake at its outer end, with means to provide a pair of spaced outlets for said chamber and with means to provide a pair of spaced tubular conducting passages leading from the outlets for the valve chamber to said combined fluid discharge outlet and air intake, a combined valve cage and guide element including an annulus bearing against the lower face of the outer flange forming means and a circular row of spaced arms carried by and adjacent the inner and outer edges of the annulus and bearing against the inner side face of the said outer flange forming means, and a sealing element bearing against the lower face of said annulus and adapted to seat on the edge of the container neck to provide a seal for the inner portion of said structure and for retaining said annulus in position, said sealing element being in the form of an annulus.
2. In a non-refillable attachment for containers of the neck type, a structure having respec-

tively an annular inner portion for connection to the container neck, an inwardly extending inner flange forming means at the outer end of said inner portion, an inwardly extending outer flange forming means overhanging said inner flange forming means and means coacting with said outer flange forming means to provide a valve chamber for the reception of a pair of superposed valves, said chamber having an inner portion of uniform diameter and an outer portion of frusto-conoidal contour, said structure being formed respectively with means to constitute a closable fluid discharge outlet and air intake at its outer end, with means to provide a pair of spaced outlets for said chamber and with means to provide a pair of spaced tubular conducting passages leading from the outlets for the valve chamber to said combined fluid discharge outlet and air intake, a combined valve cage and guide element including an annulus bearing against the lower face of the outer flange forming means and a circular row of spaced arms carried by and adjacent the inner and outer edges of the annulus and bearing against the inner side face of the said outer flange forming means, a resilient disc valve loosely mounted on said annulus and encompassed by said arms, said valve having a cavity in its upper face, a globular valve normally mounted in said recess and providing a weighting means for the disc valve, and a sealing element bearing against the lower face of said annulus and adapted to seat on the edge of the container neck to provide a seal for the inner portion of said structure and for retaining said annulus in position, said sealing element being in the form of an annulus.

3. In a non-refillable attachment for containers of the neck type, a structure being formed respectively with means for connecting it to and for extending forwardly from the neck of the container, spaced valved controlled tubular conducting off passages, a rear internal flange at the forward end of and extending inwardly from said means, a valve chamber closed at its forward end, open at its rear end and communicating with said passages, a forward internal flange forming the rear wall portion of said chamber and overhanging the rear flange, an annulus seated against the rear face of the forward flange and having its outer edge bearing against the free edge of the rear flange, a circular row of spaced arms carried by the annulus extending into said chamber and bearing against the free edge of the rear flange, and a combined sealing and retaining element bearing respectively against the inner face of said means, the rear face of said rear flange and the rear face of the annulus, said element for seating on the edge of the neck of the container.

JACOB W. SCHIEBER. 60
